UNITED STATES PATENT OFFICE.

WILLIAM N. ALLAN, OF SAN ANTONIO, TEXAS.

DRIVING MECHANISM FOR AUTOMOBILES AND THE LIKE.

1,257,776.

Specification of Letters Patent. Patented Feb. 26, 1918.

Application filed August 26, 1913, Serial No. 786,640. Renewed August 11, 1917. Serial No. 185,797.

To all whom it may concern:

Be it known that I, WILLIAM N. ALLAN, a citizen of the United States, residing at San Antonio, in the county of Bexar and State of Texas, have invented new and useful Improvements in Driving Mechanism for Automobiles and the like, of which the following is a specification.

This invention relates to improvements in automobile driving mechanism, and the primary object of the same is to dispense with the usual form of transmission gearing and differential and to replace these latter mechanisms by power devices relatively coacting through the medium of a liquid of any character, preferably oil, maintained at a predetermined volume within the several parts and completely filling the chambers of the mechanisms replacing the usual transmission gearing and differential and also in conveying means between the said parts or organizations, so that the least modification or change of pressure at one point will be instantly applied through the transmission of the column or quantity of oil with relation to the remaining part or parts without the lost motion or variation in the power applied to the respective parts. A further object of the invention is to provide substitute mechanisms or organizations for the usual transmission gearing and differential having a noiseless operation and under complete control of the chauffeur or driver of the vehicle or automobile as to stopping and starting operations, the substitute organizations for the transmission gearing being directly connected to the motor shaft. A further object of the invention is to provide substitute organizations for the usual transmission gearing and differential having conveying or pipe connecting means and controlled as to transmission of motion or power from one organization to the other by a predetermined quantity of oil which may be properly termed a static column which is automatically maintained at a uniform pressure, the substitute organization being readily capable of reverse movement and the differential so arranged as to accommodate the variation of speed on the two sides of the machine when turning in either direction, or when the one rear wheel, for instance, moves faster than the other in traveling over curves or around corners or other places.

The invention consists in the construction

and arrangement of the several parts which will be more fully hereinafter described and claimed in preferred form and subject to such modifications and variations as fairly fall within the scope of the invention.

In the drawings:

Figure 1 is a top plan view of the running gear of an automobile shown broken through in parts and embodying the features of the invention.

Fig. 2 is a longitudinal vertical section taken in the plane of the line 2—2, Fig. 1.

Fig. 3 is a section taken in the plane of the line 3—3, Fig. 1.

Fig. 4 is a cross-section taken in the plane of the line 4—4, Fig. 1.

Fig. 5 is a transverse vertical section taken in the plane of the line 5—5, Fig. 2.

Fig. 6 is a top plan view of the sliding block of the secondary power generator or circulator.

Fig. 7 is a detail elevation of the front plate or head of the casing of the secondary generator or circulator.

Fig. 8 is an enlarged top plan view particularly showing the secondary generator or circulator.

Fig. 9 is a transverse section taken in the plane of the line 9—9, Fig. 8.

Fig. 10 is a longitudinal section of the pressure controller or regulator.

Fig. 11 is an enlarged detail section of the check valve coöperating with the pressure controller or regulator.

Fig. 12 is a horizontal section through the improved differential showing portions of the sectional or two part drive axle.

Fig. 13 is a transverse vertical section through portions of the differential.

Fig. 14 is a section taken in the plane of the line 14—14, Fig. 13.

Fig. 15 is a cross-section through one of the differential rotors particularly showing the antifrictional bearings for the blades or vanes.

Fig. 16 is a transverse section on the line 16—16, Fig. 15.

The chassis 5 may be of any preferred form and embodies cross-braces 6, 7 and 8 which serve as supports for the mechanism which will be hereinafter explained. In the front portion of the chassis the usual form of motor 9 is mounted and has a rearwardly projecting shaft 10. In the rear part of the chassis the usual shaft or axle is mounted in suitable bearings and in the present in-

stance comprises two parts 11 and 12 in longitudinal alinement and respectively having thereon the drive wheels 13 and 14.

A secondary power generator or circulator 15 is mounted between the cross-braces or supports 6 and 7 in the center of the chassis and rests upon a pair of longitudinal frame bars 16 secured to the braces or supports 6, 7 and 8. This secondary power generator or circulator 15 is shown on an enlarged scale in section by Figs. 2 and 3 and comprises a surrounding or inclosing casing 17 with a sliding block or pump element 18 mounted therein, actuated at the will of the chauffeur or driver 15 by a pull-rod or connecting element 19 secured to the center of one end thereof and extending through a gland 20 in one end of the casing 17 to adjusting means on one side of the chassis which will be presently explained. The block or pump element 18 is of materially less dimensions in one direction, or is of less length than the interior of the casing 17 so that the said block or element may be readily shifted. The block or element 18 is formed with a cylindrical chamber 21 having a cylindrical rotor 22 eccentrically mounted therein and provided with a plurality of extensible blades or vanes 23 which are equipped with rollers 24 at opposite portions, the said rollers 24 continually engaging cam grooves 25 in the end walls 26 of the block or element 18, the said cam grooves 25 being concentric with relation to the chamber 21, but eccentric with relation to the rotor 22. The rollers 24 are mounted on rods or bearing devices 27 secured to or in the blades or vanes 23, the blades or vanes working preferably in sockets 28 fitted in the rotor 22, as clearly shown by Fig. 5, said sockets being adapted to resist wear in view of the fact that they are made of harder material than the remaining portion of the rotor, and by this means the blades or vanes 23 will be maintained in practical working condition. The blades or vanes 23 also have suitable packing strips 29 at their outer ends which may be of the usual spring-pressed type to set up a tight engagement or joint between the outer ends 45 of the blades or vanes and the portion of the wall of the chamber 21 with which the blade or vane ends are adapted to coöperate. The rotor 22 is keyed on the rear projecting portion of the motor or engine shaft 50 10 which extends through the casing 17 to the rear side of the latter, as shown by Fig. 3, and also through the block or element 18, the latter having horizontally disposed slots 30 in opposite ends thereof or at the front 55 and rear portions to accommodate the shifting movement of the said block or element relatively to the shaft, one of the ends of the block being shown in detail by Fig. 7. By means of the slotted end construction just 60 explained, the rotor is always maintained in

one position in the casing 17 or is not shifted while the block or element 18 is moyed to modify the space in the chamber 21 relatively to either side portion of the rotor in changing from a forward drive to a reverse 70 drive of the automobile or machine as a whole. The upper part or top portion of the block or element 18 is formed with a plurality of inlets or ports 31, as clearly indicated by Fig. 6, and the lower part of 75 said block or element is likewise formed with a plurality of outlets 32, or the outlets 32 may become the inlets, and the inlets 31 the outlets, in accordance with the direction of movement of the automobile or machine 80 when the block or element 18 is adjusted or shifted from one position to another within the casing 17. The inlets 31 and outlets 32 communicate or open into diametrically opposite portions of the chamber 21 or are 85 adapted to respectively communicate with upper and lower chambers 33 and 34 to which pipes 35 and 36 are respectively attached and have continuous communication. Between the points of attachment and communication 90 of the pipes 35 and 36 with the chambers 33 and 34 and at the rear of the secondary generator or circulator, a neutral valve 37 is disposed and extends transversely through the said generator or circulator at the point 95 where it is applied and is mounted to rotate so as to set up communication between the pipes 35 and 36 or between the chambers 33 and 34 when the said valve is turned to open ports 38 extending through the valve, 100 as shown by Figs. 3 and 9, when it is desired to permit the engine and the secondary generator or circulator to run without actuating the differential or in case the engine or motor and secondary generator are shut off and 105 stopped to permit the liquid medium to circulate backwardly and forwardly through the pipes 35 and 36 while the automobile or other vehicle is coasting or when the operation of the engine or motor and secondary 110 generator is unnecessary. When the valve 37 is turned to bring the ports 38 thereof in planes at right angles to the position of the said ports shown by Figs. 3 and 9, the circulation of the liquid medium can be effected 115 only through the rotor 22 or the chamber 21 in which the said rotor operates, and during such latter position of the valve the automobile or other vehicle will be driven either forwardly or backwardly in accordance with 120 the position of the rotor 22. The valve 37 has a stem 39 projecting outwardly from one end thereof through a gland or stuffing box 40 to one side of the chassis, as shown by Fig. 1, and has its outer end held in a 125 suitable bearing 41, the said stem being provided with a foot-operating lever 42 which extends upwardly through the flooring or bottom of the body of the automobile or other vehicle within easy reaching distance 130

of the foot of the chauffeur or driver. The valve 37 may be properly termed a neutral valve and mainly affects by its position the operation of the substitute for the usual 5 differential, which in the present instance is in the form of a fluid operated differential, generally designated by the numeral 43 and to opposite extremities of which the sectional or two-part drive axle extends. As shown 10 by Fig. 1, the fluid operated differential 43 embodies a casing 44 centrally divided by a partition wall 45 forming two independent chambers 46 and 47, as clearly shown by Fig. 12. A rotor 48 is secured on the section or part 12 of the drive axle extending 15 through the chamber 46 and a rotor 49 is secured on the section or part 11 of the drive axle extending through the chamber 47, said rotors occupying eccentric positions relatively to the chambers 46 and 47, as clearly 20 shown by Fig. 13, and the outer portions of the chambers 46 and 47 are respectively closed by heads 50 and 51 secured against the casing, as shown, and having glands or 25 stuffing boxes 52 and 53 projecting therefrom, as shown by Fig. 12.

The rotors 48 and 49 have rollers 54 at opposite ends which engage cam grooves 55 in the opposite heads 50 and 51, the said cam 30 grooves being eccentrically formed in the heads and directly connecting with blades or vanes 56 of the rotors 48 and 49. In view of the eccentricity of the cam grooves 55 in the heads 50 and 51 the blades 56 will be regularly projected, as clearly shown 35 by Figs. 13, 15 and 16. Each rotor 48 or 49 is similarly equipped with the blades or vanes 56 and has radial sockets 57 mounted therein, as clearly shown by Figs. 13 and 40 15, of harder material than the remaining portion of the rotor to take up wear, and the blades are directly seated and move in the said sockets, the outer ends of the blades being provided with packing strips 58 of the 45 usual spring-pressed type to frictionally engage the walls of the chambers in which the blades have movement. Each blade 56 is also provided with an antifrictional attachment, and to receive said attachment the one 50 side of the blade is longitudinally recessed, as at 59, and is provided with an inner wear plate 60 of harder metal than the blade, and bearing against the said wear plate is a plurality of rollers 61 held between washers 55 or partitions 62, the outer partition 62 being engaged by springs 63 arranged as clearly shown by Fig. 16 and operating to 60 keep the rollers in operative position relatively to each blade. By means of the antifrictional attachment as just explained each blade 56 is permitted to have sensitive sliding movement in its socket. The partitions 62 form the outer and inner extremities of an inclosure or seat 64 for the reception of 65 the rollers 61, as shown by Fig. 16, the said

seat being open at its opposite sides so as to expose and permit contact of the opposite portions of the rollers respectively with the plate 60 and the adjacent wall of the socket 57. Through the medium of the antifrictional attachment in connection with the blades or vanes 56 wear on the latter is reduced to a minimum, and, furthermore, by means of the sockets 57 the blades or vanes are retained in proper radial alignment and 70 the use of a less expensive grade of material for the main portions of the rotors 48 and 49 is permitted without detracting in the least from the effective operation of the 75 said rotors.

An opening 65 is formed in the partition 45 to receive the inner ends of the sectional or two-part driving axle composed of the sections 11 and 12, the inner ends of the sections normally abutting, as clearly shown 80 by Fig. 12, and the opening 65 is enlarged at opposite sides of the center of the partition 45, as at 66, and in the enlargements of the opening antifrictional bearings 67 are mounted and are internally constructed, as 85 clearly shown by Fig. 14. The heads 50 and 51 also have central openings 68 in which antifrictional bearings 69 are mounted and of the same construction as the bearings 67, the sections or parts 11 and 12 of the axle 90 extending through the bearings 69 and outwardly through the centers of the stuffing boxes 52 and 53. The inner ends of the sections or parts 11 and 12 of the axle are longitudinally bored, as at 70, to receive a 100 coupling axle or rod 71 which is loosely projected into the opposite bores, as shown by Fig. 14, so that the said sections or parts 11 and 12 may rotate at different rates of speed when the automobile or vehicle is 105 turned either to the right or left and at the same time be maintained in proper operative relation. The stuffing boxes 52 and 53 each specifically embodies a cylindrical seat 72 extending outwardly from the center of the adjacent head 50 or 51 and having a non-leaking joint formed by a gland washer 73 closely embracing and surrounding the section of the axle passing outwardly 110 through the stuffing box. Telescopically fitted within the outer open end of the cylindrical seat 72 is a hollow closing cap 74 which is fully open at its inner end and has a central opening as at 75 at its outer end through which the one section or part of 115 the axle extends. The cap 74 is adjustable relatively to the seat 72 and is held in place by a locking cap 76 applied thereover and internally screw-threaded, as at 77, to engage outer screw-threads 78 of the seat, as 120 clearly shown by Fig. 12. The advantage of this improved stuffing box is that a long stuffing space is provided and the stuffing material may be disposed in the seat and the closing cap 74 and the locking cap 76 130

afterward applied without in the least affecting the assemblage of the cap 74 with the seat 72 and without in the least displacing or winding the packing material 5 within the stuffing box, with material advantages in the rotation of the section or part of the axle passing through the stuffing box as well as preventing the least leakage of the oil through either bearing 69. Se- 10 cured to the heads 50 and 51 are frustoconical guards 79, each having a hand-hole with a suitable closure, as at 80, to permit access to the stuffing boxes for the purpose of filling and adjusting the same. The guards 79 15 also have cylindrical extensions 81 with sleeves 82 fitted therein and surrounding the outer extremities of the sections or parts 11 and 12 of the axle, the sleeves 82 extending out to the hubs of the wheels 13 and 14 to 20 provide a strong support for the latter and also to completely inclose the parts of the axle and the opposite extremities of the differential to obviate the entrance of dust or dirt to the latter.

25 The casing 44 of the differential has enlarged chambers 83 and 84 at the upper and lower portions of the inner side thereof with which the rear ends of the pipes 35 and 36 respectively communicate, and through 30 openings or ports 85 the chambers 46 and 47 have communication with the said enlarged chambers 83 and 84, the latter chambers serving as a means of distribution of the liquid or oil equal with regard to quantity 35 and pressure relatively to the two rotors 48 and 49 of the differential. The openings or ports 85 are located at points above and below each rotor, as shown by Fig. 13, and a dividing wall 86 is located at the outer por- 40 tion of each chamber 83 and 84 to regularly separate the flow of liquid or oil relatively to the chambers 46 and 47. The pipes 35 and 36 are suitably attached to an inner side plate 87 of the differential casing 44, as 45 shown by Fig. 13, and the parts of the chambers 83 and 84 are so shaped and have such relative positions to the ports or openings 85 and the chambers 46 and 47 that the liquid or oil will have unimpeded circulation into 50 and outwardly from one chamber and around each rotor 48 and 49 to act on the blades 56 as the latter are radially projected.

A pressure regulator or controller is embodied in the improved driving mechanism 55 and co-operates with the secondary power generator or circulator 15, said pressure regulator or controller consisting of a cylinder 87 of suitable length having front and rear caps 88 and 89, as shown by Fig. 10, 60 and therein a piston 90 is mounted and has a stem 91 movably engaging the rear cap 89 and adapted to slide through the latter. Surrounding the piston rod 91 and bearing at its opposite extremities respectively 65 against the piston 90 and the rear cap 89 is

a spring 92 which tends to force the piston forwardly or toward the cap 88. Connected to the center of the cap 88 and communicating with the cylinder is a charging pipe 93 having at its outer free extremity a 70 charging valve 94 and provided at an intermediate point with a T-coupling 95 for a connecting pipe 96 provided with a check valve 97 and attached to the top portion of the secondary power generator or circulator 15, as at 98, see Figs. 5 and 8. The pipe 96 communicates with the upper chamber 33 of the secondary power generator or circulator 15. As shown by Fig. 11, the check valve 97 has the usual passage 99 there- 75 through, together with a valve seat 100 and a gravitating valve 101. The gravitating valve 101, however, differs from the ordinary check valve in having a small opening 101^a therethrough, said opening being only 80 sufficiently large to permit relief of excessive expansion by a leak back of the oil or liquid above the valve and return thereof into the cylinder 87 under certain excess pressure conditions or when an equilibrium 90 of pressure on opposite sides of the valve 101 is not present. The improved mechanism also includes a pressure equalizer or safety valve which is associated with the rear portion of the secondary power genera- 95 tor or circulator 15 at one side of the points of communication or attachment of the pipes 35 and 36 with the said generator or circulator and adjacent to the valve 37. This safety valve embodies a supplemental cyl- 100 inder 102 having therein a floating or loosely arranged cylindrical valve or piston 103 slidably mounted on a rod 103^a held at its ends in the cylinder ends and engaged at opposite ends by opposing springs 104 and 105, by-passes 106 and 107 having open communication with the cylinder 102 at points above and below the normal intermediate position of the valve or piston 103, as clearly shown by Fig. 9. The upper and 110 lower portions of the cylinder 102 have ports 108 and 109 opening into the rear por- 115 tions of the upper and lower chambers 33 and 34 adjacent to the point of communica- 120 tion with the latter of the pipes 35 and 36 and above and below the valve 37. The purpose of this safety valve is to provide for an equalization of excessive pressure that may be suddenly generated within the circu- 125 lating system and due to abnormal pressure that may arise from a sudden stopping of the secondary power generator or circulator or of the motor of the automobile, as in reversing the movement of the latter or from any other cause, and thus relieve the 130 circulating pipes 35 and 36 as well as the remaining parts of the mechanism from undue strain that might without relief result seriously or effect a breakage or fracture of the pipes. Should this excessive 130

pressure occur in either pipe 35 or 36, the valve 103 will be moved in a corresponding direction, as for instance if excessive pressure took place in the pipe 35 the increased 5 pressure would be transmitted through the port 108 downwardly through the cylinder 102 against the top of the valve 103 and compress the lower spring 105 until the said valve 103 was moved downwardly far 10 enough to open up communication between the by-pass 107 and the upper portion of the cylinder 102, when an immediate relief would be effected, and conversely if the excessive pressure took place in pipe 36 the 15 valve 103 would be moved upwardly by reason of the fact that the increased pressure would be brought to bear upon the valve 103 through the ports 109 and when the valve 103 was moved upwardly the upper spring 20 104 would be compressed and the relief take place when the valve cleared the lower by-pass 107 for communication with the upper part of the cylinder 102, the movement of the valve in either direction and opening 25 communication between the by-passes 106 and 107 establishing a counter-circulation in either direction through the ports 108 and 109 and the cylinder 102 when either of the by-passes 106 and 107 is opened respectively to the lower and upper portions 30 of the cylinder 102 by corresponding movement of the valve 103. Under normal conditions the springs 104 and 105 hold the valve 103 in central position in the cylinder 35 102, as shown by Fig. 9, the said springs having such normal tension as to resist movement of the valve 103 by the ordinary or normal pressure of the liquid or oil circulating in the mechanism. The pressure 40 in the regulator 87 is between forty and fifty pounds, and this pressure is produced by the compression of the spring 92 which is added to the normal pressure of the liquid or oil primarily introduced in the circulating system under pressure.

The pipes 35 and 36 may be of any form 45 adapted for the purpose of setting up circulatory communication between the secondary power generator or circulator and the differential, but it is preferred that these pipes be of corrugated form as shown, as by such construction they are rendered much more resistful to strain, and it is preferred also in many instances to use a sheet steel 50 tube 110 in each pipe so as to prevent what is known as skin friction, that might result with disadvantage at times in the corrugated form of pipe. These steel tubes 110 in each of the pipes just specified are held 55 in fixed position relatively to said pipes. The secondary power generator or circulator 15 and the differential 43 each has an air chamber 111 and 112 communicating with the upper portion thereof and adapted to 60 permit any air that may be in the several

parts of the mechanism to escape therefrom when the mechanism is charged, and at such time a valve 113 on each cylinder 111 and 112 is open to allow the air to escape to the atmosphere. After the mechanism is 70 charged with liquid or oil the valves 113 are closed, and it will be understood that at any time found necessary when the mechanism is charged to liberate air therefrom the valves 113 may be opened at will.

The adjusting rod 19 connected to the slide block 18 of the secondary power generator or circulator 15 is operated by a slide plate 114 mounted in suitable guides 80 of one of the side bars or frame beams 85 of the chassis, the slide plate 114 having a diagonal slot 116 therein engaged by a roller 117 depending from and carried by a head 118 secured on the outer end of the rod 19. Attached to the rear end of the 85 plate 114 is an operating or connecting rod 119 movably secured to the lower end of a lever 120 suitably mounted on the same side bar or frame beam in rear of the plate 114 and having a suitable locking means co-operating with a toothed segment 121. It will be understood that the lever 120 will be of any approved type and will project upwardly within easy reaching distance of the chauffeur or driver of the machine. By 90 shifting the lever 120 backwardly and forwardly the plate 114 will be correspondingly moved and through the medium of the diagonal slot 116 the rod 19 will be moved outwardly and inwardly to change the position of or shift the block 18 and dispose the latter either directly in the center of the casing 17 or in advance or in rear of the center of said casing as may be desired.

The apparatus is charged with a liquid, 105 preferably oil, through the charging valve 94 of the pipe 93, a suitable pressure pump being used and attached to the said valve. The oil is pumped into the pipe 93 and passes through the pipe 96 and check valve 110 97 to the upper chamber 33 and then through the chamber 21 around the rotor 22 down to the chamber 34 and through the lower pipe 36 to the differential 43, and then forwardly again through the pipe 35 to the 115 upper chamber 33. The pumping of the oil into the pipe 93 is continued until the mechanism is fully charged and the desired pressure established, the determined pressure being ascertained through the medium 120 of any suitable form of gage on the pump, and during the establishment of the pressure in the mechanism the piston 90 will be pressed backwardly in its cylinder 87 against the resistance of the spring 92 and 125 the piston rod 91 will recede through the rear cap 89. When an equilibrium of pressure has been established on opposite sides of the check valve 101 the latter will seat itself by gravity, and should there be a re- 130

laxation of the pressure above the check valve the latter will be immediately forced upwardly from its seat and the pressure restored to normal condition through the 5 operation of the regulator or controller embodying the piston 90 and spring 92, the spring pressure being added to the normal pressure or at least tending to maintain an equilibrium on the slightest fluctuation of 10 pressure above the check valve 101 or in the main portion of the mechanism. A tendency to fluctuation or variation of the pressure in the mechanism above the check valve 101 will always be present owing to the centrifugal action of the rotor 22 of the generator or circulator 15 when running at high speed, and this tendency to variation of pressure is overcome and a uniformity of 15 pressure in the entire oil circuit is maintained by the pressure regulator or controller embodying the piston 90 and the spring 92. When the expansion is greater on one side or the other, as for instance 20 on the return side or through the pipe 25 36 when the automobile or car is reversed, or from any other cause during the operation of the mechanism, and when the one rotor of the differential is running faster than the other, the pressure regulator 30 or controller embodying the piston 90 and spring 92 is affected by the oil being forced downwardly through the small opening 101^a in the check valve 101, and this additional pressure will be imposed on the piston 90 35 and the latter will thereby be forced backwardly a distance corresponding to the greater pressure on either one side or the other or in the pipe 36 or pipe 35 until normal conditions are resumed relatively to the 40 circulation of the oil in the mechanism, and at such latter time the piston 90 will again automatically assume its proper position relatively to an equilibrium of pressure or to set up an equilibrium of pressure 45 throughout the entire mechanism. It will be understood that all the parts of the mechanism are fully charged with oil at all times, and should there be any leakage or shrinkage from any cause whatsoever the 50 deficiency will be made up by the operation of the pressure regulator or controller. At any time desired the mechanism may be subjected to an auxiliary charging with oil and it is obvious that such operation will 55 have to be pursued from time to time.

The mechanism having been charged with oil as just explained will then be ready for operation and when the automobile or car is standing, the block or element 18 will have 60 been shifted to or occupies a position directly on center relatively to the casing 17 and shaft 10, the lever 120 then being perpendicular. When the block 18 is directly 65 in the center of the casing 17 the rotor 22 will be likewise disposed in the center of the 70 chamber 21, and if the rotor 22 is running by actuation of the motor 9 through the shaft 10 there will be no oil transferred from the inlet chamber 33 to the outlet chamber 34 as all the parts are on center, or the oil 75 in the several parts of the apparatus will remain without circulation or be practically inert and consequently the oil will have no effect on the rotors 48 and 49 of the differential 43. To start the car or automobile, the 80 motor 9, if it has stopped running, will be first set in motion, or if the motor is running and the rotor 22 is in actuation the lever 120 is moved slightly forwardly and the block 18 is thereby slightly shifted to the left and off 85 center. This movement of the block will cause the formation of a larger space in chamber 21 on the left side of the rotor 22 than on the right side of said rotor, and the blades 23 will be caused to carry the liquid 90 from the inlet chamber 33 to the outlet chamber 34 and force the oil through the pipe 35 into the lower chamber 84 of the differential in the direction of the arrows shown by Figs. 3 and 13, thereby revolving the rotors 95 48 and 49 and driving the sections or parts 11 and 12 of the rear drive axle or shaft. It will be understood that the oil passes from the lower chamber 84 into the lower portions 100 of the chambers 46 and 49 through the lower 95 ports 85, and after engaging the blades 56 of the rotors 48 and 49 the oil passes upwardly to the upper chamber 83 and returns through the pipe 36 to the top portion or upper chamber 33 of the secondary power generator or circulator 15, and by this direction of circulation the automobile or motor will be driven forwardly and the circulation will be regularly carried on downwardly and 105 backwardly and then upwardly and forwardly and coöperate with the rotors 22 and 48 and 49. The speed of the rotors 48 and 49 will depend entirely on the amount of liquid pumped or circulated rearwardly by the rotor 22, or in other words this speed 110 will depend upon the distance the block 18 is off center and will be controlled by the lever 120. During the operation of the mechanism as just explained, the neutral valve 37 will be closed and remain closed 115 during both forward and reverse movements of the automobile or car. A reverse movement of the automobile or car is effected by moving the block 18 through actuation of the lever 120 in a direction opposite to that just 120 described, or the block 18 will be shifted to the right and off center, and under these conditions the oil will be thrown upwardly into the chamber 33 and pass rearwardly through the pipe 36 to the upper chamber 83 of the 125 differential and thence enter the upper portions of the chambers 46 and 47 and reversely rotate the rotors 48 and 49 and the sections or parts 11 and 12 of the drive shaft or axle, the oil returning through the lower 130

pipe 35 from the lower chamber 84 back to the rotor 22. If the automobile or car is in motion and it is desired to coast down a hill when the motor or engine 9 should be slowed down or stopped, the valve 37 is opened, as shown by Figs. 3 and 9, and as hereinbefore explained circulation of the oil is then effected through the valve instead of passing forwardly to the rotor. Furthermore, this 5 valve 37 is opened when it is desired to bring the automobile or car to a standstill without stopping the motor 9 or the rotor 22, and when the valve 37 is open it will be understood that the oil will circulate around the 10 rotors 48 and 49 without actuating the sections or parts 11 and 12 of the drive axle or shaft owing to the fact that the secondary power generator or circulator rotor 22 is not imparting to the oil any forceful or driving 15 impulse. When the machine is brought to a standstill without stopping the motor or the rotor 22, it will be understood that the block 18 will be shifted so as to bring the same on center and thereby throw the rotor 22 out of 20 commission. When it is desired to again fully start the vehicle or set up a full circulation of the liquid or oil, the valve 37 is closed and the block 18 shifted slightly to the 25 left to bring the rotor off dead center and immediately the full circulation of the liquid or oil will be set up and the machine proceed.

The neutral valve 37 also has the additional function of operating as a braking 30 means for the rotors of the differential after the shiftable pumping element or block 18 with the rotor therein has been moved to a position where it ceases to circulate the liquid medium, said braking operation being 35 accomplished by gradually closing the neutral valve and obstructing the free circulation of the liquid medium and thereby gradually bringing the full force of the liquid medium against the rotors of the differential. A further advantageous improvement in the 40 present mechanism is the fact that the conduits 35 and 36 are flexible and fracture thereof is less liable to ensue, especially in view of the use of the corrugated outer pipe as a part of each conduit and also the use of 45 the inner thin sheet metal tube, which, combined with the outer corrugated tube, produces a strong conduit organization, and as these conduits are permitted to flex they will be also less liable to injury by pressure or 50 expansion therein and from sudden vibrations or jars produced by the running of the vehicle or automobile. A further advantage is the embodiment in the organization as a whole of the neutral valve, the expansion 55 equalizer, and the pressure regulator as all 60 65

contingencies or conditions can be readily met in a practical manner by the operation of these several parts either coördinately or at times independently.

From the foregoing it will be seen that the organizations used as specified for the usual transmission gearing and differential mechanisms are noiseless in their operations and readily controllable to meet various operating contingencies of automobiles and other 70 analogous vehicles or propelling motor mechanisms. Furthermore, the parts of the improved attachments or the organization as a whole may be readily installed in operative position on the chassis, and the maintenance of the improved mechanism in working order will be economical in view of the fact that the parts are so constructed that they will not readily become broken or disorganized or have the numerous disadvantages 75 of gearing or other devices ordinarily used in transmission gearing and differential organizations for automobiles and analogous machines.

What is claimed is:

1. A driving mechanism for an automobile and the like, comprising a motor having a shaft, a secondary power generator or circulating organization embodying a shiftable pumping element connected to said shaft 90 and having upper and lower chambers, a rear drive shaft comprising independently rotatable sections each provided with a rotor, a casing having independent chambers in which the rotors of the drive shaft are mounted and also provided with upper and lower circulating chambers in communication with the said independent chambers, single tubular conduits between the upper and lower chambers of the casing and the 95 secondary generator, the generator, conduits and casing being filled with a fluid medium to full capacity, the reversal of movement of the several parts being effected through the same conduits, and means forming a 100 part of the secondary power generator and disposed between the points of communication of the conduits with the upper and lower chambers of the generator for changing the circulation of the fluid medium 105 through a portion of the generator and between the said generator and the chambers and rotors of the drive shaft sections.

2. A driving mechanism for an automobile and the like comprising a motor, a secondary power generator or circulating organization embodying a shiftable pumping element actuated by said motor, a rear drive shaft embodying independently rotatable sections individually provided with a rotor, 120 a casing having independent chambers in which the rotors of the drive shaft are mounted and also provided with upper and lower chambers in communication with the said rotor chambers, single tubular conduits 125

between the said upper and lower chambers of the casing and the secondary generator, the conduits, generator and chambers being filled with a liquid medium to full capacity under pressure, means for maintaining the liquid under pressure, and a neutral valve forming a part of the secondary power generator and located between the tubular conduits connected to the secondary power generator or circulating organization for establishing a free circulation of the liquid medium relatively to said rotors when the pumping element is in neutral position.

3. A driving mechanism for an automobile and the like comprising a motor, a circulating organization embodying a shiftable pumping element operated by said motor and serving as a substitute for the usual transmission mechanism, a rear drive shaft embodying independently rotatable sections individually provided with a rotor and serving as a substitute for the usual form of differential, single tubular conduits between the circulating organization and the rotors of the drive shaft, the said conduits, circulating organization and rotors of the drive shaft having a liquid under pressure flowing therethrough and operating thereupon, means for maintaining the liquid under pressure, and means embodied in the circulating organization for maintaining a circulation of the liquid through the rear portion of the circulating organization and with relation to the rotors of the drive shaft sections without stopping the motor and the actuation of the said circulating organization.

4. A driving mechanism for an automobile and the like comprising a motor, a circulating organization embodying a shifting chambered element with a rotor therein connected to the motor, a rear drive shaft embodying independently rotatable sections, a casing having independent chambers with rotors therein fixed on the sections of the drive shaft and also provided with upper and lower chambers in communication with the rotor chambers, single conduits between the upper and lower portions of the circulating organization and the upper and lower chambers of the said casing, the said single conduits and chambers being filled to full capacity with liquid under pressure and the said conduits adapted to alternately serve as feeding and return means relatively to the circulating organization and chambers and rotors of the drive shaft in accordance with the position of the shifting chambered element of the circulating organization, means for maintaining the liquid under pressure, and means forming part of the circulating organization and located between the points of attachment of the conduits thereto for effecting circulation of the

liquid independently of the circulating organization.

5. A driving mechanism for an automobile and the like comprising a circulating organization having upper and lower chambers and embodying a shiftable pumping element between and in continuous communication with said chambers, a rear drive shaft embodying independently rotatable sections individually provided with a rotor, upper and lower distributing chambers and independent chambers between the latter upper and lower chambers and having the drive shaft rotors therein and always communicating with the said upper and lower distributing chambers, single tubular conduits between the upper and lower chambers of the circulating organization and the upper and lower chambers of the rotors of the drive shaft for the circulation of a liquid operating medium which is maintained under pressure relatively to the circulating organization and said rotors of the drive shaft, means for maintaining the liquid under pressure, and an automatically operating safety valve also included in the circulating organization to compensate for and equalize excessive pressure.

6. A driving mechanism for an automobile and the like comprising a motor having a shaft, a circulating organization embodying a shifting chambered element with a rotor therein directly connected to and actuated by the shaft of the motor, a rear drive shaft embodying independent rotatable sections, a casing having independent chambers with rotors therein fixed on the sections of the drive shaft and also provided with upper and lower chambers in communication with the rotor chambers, upper and lower single conduits between the upper and lower portions of the circulating organization and the upper and lower chambers of the casing, the said conduits alternately operable through the actuation of the rotor of the circulating organization as feed and return mediums and said conduits together with the chambers and circulating organization being filled to full capacity with a liquid under pressure, a pressure regulator connected to the upper portion of the circulating organization and automatically operative to maintain a constancy of pressure and normally partially filled by the liquid under pressure to give the necessary compression to the liquid, and a check valve between the said pressure regulator and the circulating organization and provided with means for automatically relieving excessive pressure.

7. A driving mechanism for an automobile and the like comprising a motor having a shaft, a circulating organization embodying a shifting chambered element with a

5   rotor therein directly connected to and actuated by the shaft of the motor which extends into the said organization, the latter organization also being provided with upper and lower chambers between which the said element is located, a rear drive shaft embodying independent rotatable sections, a casing having independent separated chambers with rotors therein fixed on the sections 10   of the drive shaft and also provided with upper and lower chambers with which said separated chambers continually communicate, upper and lower single conduits between the said upper and lower chambers 15   of the circulating organization and the chambers of the casing, the said conduits alternately operable through the actuation of the rotor of the circulating organization as feed and return mediums and said conduits together with the chambers and circulating organization being filled to full capacity with a liquid under pressure, a pressure regulator connected to the upper chamber of the circulating organization and automatically operative to maintain a constancy 20   of pressure with relation to the entire mechanism and provided with means for filling the same, and a check valve interposed between the pressure regulator and the circulating organization, having provision for automatically relieving excessive expansion and pressure during certain movements of 25   the automobile.

30   8. A driving mechanism for an automobile and the like comprising a circulating organization having upper and lower chambers and embodying a shiftable pumping element between and in communication with said chambers, a rear drive shaft embodying independently rotatable sections individually provided with a rotor, upper and lower distributing chambers adjacent to the drive shaft, independent chambers having the drive shaft rotors therein and communicating with the said upper and lower distributing chambers, upper and lower single tubular conduits respectively and directly connected to the upper and lower distributing chambers and also to the upper and lower chambers of the circulating organization and through which also the circulation is reversed when reversing the movement of the driving mechanism, the said conduits being continually open, an automatically operating safety valve also included in the circulating organization to compensate for and equalize excessive pressure, and a pressure regulator connected to the upper chamber of the circulating organization and automatically operative to maintain a constancy of pressure in all of the chambers and the conduits. 35   60

65   9. A driving mechanism for an automobile and the like comprising a circulating

organization embodying upper and lower 65   chambers and a shiftable pumping element between said chambers, a rear casing having upper and lower independent chambers and a drive shaft therein embodying independently rotatable sections individually provided with a rotor open to the chambers, continually open tubular conduits between the circulating organization and the rotors of the drive shaft for the circulation of a liquid operating medium which is maintained under pressure relatively to the circulating organization and said rotors of the drive shaft, a pressure regulator connected to the circulating organization and having a charging connection for forcing the liquid 70   operating medium into the circulating organization and conduits and bringing such liquid medium in operative relation to the rotors of the rear drive shaft and also for charging the regulator, and a check valve 75   in said charging connection having means for automatically relieving excessive expansion and pressure from the remaining parts, the said pressure regulator being partially 80   filled through its charging connection with the liquid from the circulating organization, conduits and rear casing when the latter are charged and provided with means operating to exert a pressure greater than the normal pressure of the liquid in the parts of 85   the mechanism to maintain a uniform normal pressure in said parts. 90   95

100   10. A driving mechanism for an automobile and the like comprising a circulating organization embodying a shiftable pumping element, a rear casing having a drive shaft therein embodying independently rotatable sections individually provided with a rotor, continually open single tubular conduits between the upper and lower portions of the circulating organization and the rotors of the drive shaft for the circulation of a liquid operating medium which is maintained under pressure relatively to the circulating organization and said rotors of the drive shaft, and a regulator connected to the circulating organization and consisting of an elongated cylinder with a spring-pressed piston therein having a rod freely movable through one end of the cylinder and a check valve in said charging connection having means for automatically relieving excessive expansion and pressure from the remaining parts, the said pressure regulator being partially filled with the liquid through its front 105   end which is in charging connection with the circulating organization, conduits and rear casing when the latter are charged and provided with means operating to exert a pressure greater than the normal pressure of 110   the liquid in the parts of the mechanism to maintain a uniform normal pressure in said parts. 115   120   125

11. A driving mechanism for an automobile and the like comprising a circulating organization embodying a shiftable pumping element, a rear drive shaft embodying 5 independently rotatable sections individually provided with a rotor, continually open tubular conduits between the circulating organization and the rotors of the drive shaft for the circulation of a liquid operating medium which is maintained under pressure 10 relatively to the circulating organization and said rotors of the drive shaft, a pressure regulator connected to the circulating organization, and a check valve interposed between the said regulator and circulating organization 15 and having a valve proper therein with a reduced opening therethrough to relieve the parts of excessive pressure and expansion and prevent too rapid flow of the liquid therethrough and disturbance of the liquid supply in the several parts.
12. A driving mechanism for an automobile and the like comprising a circulating organization having upper and lower chambers 20 and embodying a shifting element with a chamber in continual communication with the said upper and lower chambers and also provided with a rotor in the chamber of the shiftable element, a motor having a shaft on 25 which the rotor of the shiftable element is mounted, a differential comprising an upper and a lower distributing chamber and independent rotor chambers conjointly in communication with the distributing chambers 30 and also having a rear drive shaft embodying independently rotatable sections individually provided with a rotor, the rotors of the drive shaft being mounted in the rotor chambers of the differential, upper and 35 lower continually open single conduits between and having communication exclusively and directly with the upper and lower chambers of the circulating organization and the upper and lower distributing chambers of the differential, all of the chambers as well as the conduits being continually open to each other, and a pressure regulator provided with means for filling the same and having a connection from one end to the 40 upper chamber of the circulating organization and automatically operative to maintain a constancy of pressure in all of the chambers and the conduits and having means for maintaining the maximum pressure in 45 all the parts, the pressure regulator being charged through its end connection with the upper chamber of the circulating organization when the latter and the conduits and chambers of the differential are charged.
- 50 13. A driving mechanism for an automobile and the like comprising a circulating organization having upper and lower chambers and embodying a shifting element with a chamber in continual communication with 55 the said upper and lower chambers and also

provided with a rotor in the chamber of the shiftable element, a motor having a shaft on which the rotor of the shiftable element is mounted, a differential comprising upper and lower distributing chambers and independent rotor chambers in communication with the distributing chambers and also having a rear drive shaft embodying independently rotatable sections individually provided with a rotor, the rotors of the drive 70 shaft being mounted in the rotor chambers of the differential, upper and lower continually open single conduits between the upper and lower chambers of the circulating organization and the upper and lower distributing chambers of the differential, all of the chambers as well as the conduits being continually open to each other, and a safety valve mounted in and forming part of the circulating organization in rear of the 75 shiftable element and having a by-pass with communicating ports therethrough to set up a short circuit between the conduits and differential and the chambers and rotors of the circulating organization, the by-pass being provided with an automatically operating sliding piston valve normally dividing the same.

14. A driving mechanism for an automobile and the like comprising a circulating organization having upper and lower chambers and embodying a shifting element with a chamber in continual communication with the said upper and lower chambers and also provided with a rotor in the chamber of the shiftable element, a motor having a shaft on which the rotor of the shiftable element is mounted, a differential comprising upper and lower distributing chambers and independent rotor chambers in communication with the distributing chambers and also having a rear drive shaft embodying independently rotatable sections individually provided with a rotor, the rotors of the drive 90 shaft being mounted in the rotor chambers of the differential, upper and lower continually open single conduits between the upper and lower chambers of the circulating organization and the upper and lower distributing chambers of the differential, all of the chambers as well as the conduits being continually open to each other, and a safety valve mounted in the circulating organization laterally as to the points of attachment of the conduits thereto and the 95 chambers and rotor of said organization and controlling the passage between the conduits and operative to set up a braking action relatively to the differential, the said safety valve having a sliding piston loosely mounted therein and provided with resisting means engaging the upper and lower portions thereof.

15. A driving mechanism for an automobile and the like comprising a circulat- 100

ing organization embodying a shiftable pumping element and upper and lower chambers, a rear drive shaft embodying independently rotatable sections individually provided with a rotor, a casing with intermediate laterally aligned chambers having the drive shaft and rotors therein and upper and lower chambers communicating with said intermediate chambers, single tubular conduits between the upper and lower chambers of the circulating organization and the upper and lower chambers of the casing for the circulation of a liquid operating medium which is maintained under pressure relatively to the circulating organization and said rotors of the drive shaft, means for maintaining the liquid operating means under pressure, and a valve between the points of connection of the conduits with the circulating organization and the shiftable pumping element to short circuit the liquid operating medium through the circulating organization independently of the circulation thereof through the shiftable pumping element, said valve being also operative to set up a braking action relatively to the rotors of the drive shaft.

16. A driving mechanism for an automobile and the like comprising a motor, a circulating organization embodying a shiftable pumping element directly actuated by the motor and also having chambers on opposite sides of the said element, a rear drive shaft embodying independently rotatable sections individually provided with a rotor, tubular conduits between the circulating organization and the rotors of the drive shaft, and a pressure equalizer located within a portion of the circulating organization and having upper and lower ports in continual communication with the chambers of the said organization and the conduits.

17. A driving mechanism for an automobile and the like comprising a motor, a circulating organization embodying a shiftable pumping element directly actuated by the motor and also having chambers on opposite sides of the said element, a rear drive shaft embodying independently rotatable sections individually provided with a rotor, tubular conduits between the circulating organization and the rotors of the drive shaft, and a pressure equalizer consisting of a chamber in communication with the circulating medium between the conduits and the shiftable pumping element and having a reversely spring engaged valve therein, and by-passes adapted to be opened by opposite movements of the valve, the said equalizing chamber having ports at opposite extremities in continual communication with the chambers of the circulating organization and the conduits.

18. A driving mechanism for an automobile and the like comprising a circulating

organization embodying a shiftable pumping element, a differential embodying independently rotatable drive shaft sections individually provided with a rotor, tubular conduits between the circulating organization and the differential, and a pressure equalizer provided with ports in continual communication with opposite portions of the circulating organization and with the conduits and having an oppositely shiftable element therein under spring engagement to equalize the expansion in various parts of the mechanism.

19. A driving mechanism for an automobile and the like comprising a circulating organization embodying a shiftable pumping element, a differential embodying independently rotatable drive shaft sections individually provided with a rotor, tubular conduits between the circulating organization and the differential, a neutral valve in the circulating organization between the conduits and the shiftable pumping element, and a pressure equalizer also interposed between the conduits and the shiftable pumping element of the circulating organization and provided with a chamber having communication at points on opposite sides of the neutral valve.

20. A driving mechanism for an automobile and the like comprising a circulating organization embodying a shiftable pumping element, a differential embodying independently rotatable drive shaft sections individually provided with a rotor, tubular conduits between the circulating organization and the differential, a neutral valve interposed between the shiftable pumping element and the conduits, a pressure equalizer also interposed between the conduits and the shiftable pumping element and having continuous communication with the circulating organization and the conduits, and a pressure regulator connected to the circulating organization.

21. A driving mechanism for an automobile and the like comprising a circulating organization embodying a shiftable pumping element, a differential embodying independently rotatable drive shaft sections individually provided with a rotor, tubular conduits between the circulating organization and the differential, a neutral valve interposed between the shiftable pumping element and the conduits, an expansion equalizer also interposed between the shiftable pumping element and the conduits and having continuous communication with the circulating organization, a pressure regulator connected to the circulating organization, and a check valve interposed between the pressure regulator and the circulating organization, the valve proper of the check valve having a small opening therethrough.

22. A driving mechanism for an auto-

mobile and the like comprising a circulating organization embodying a shiftable pumping element, a differential embodying a drive shaft composed of independently rotatable sections individually provided with a rotor, and single tubular conduits between and always fully open to and directly connecting the circulating organization and the differential and comprising outer pipes with thin sheet metal tubes therein to reduce skin friction of the circulating medium relatively to the conduits.

23. A driving mechanism for an automobile and the like comprising a circulating organization embodying a shiftable pumping element, a differential embodying a drive

shaft composed of independently rotatable sections individually provided with a rotor, and single tubular conduits between and always fully open to and directly connecting the circulating organization and the differential and embodying outer corrugated pipes with inner thin sheet metal tubes to reduce skin friction.

In testimony whereof I have hereunto set 25 my hand in presence of two subscribing witnesses.

WILLIAM N. ALLAN.
